ANTENNA POLE BASE

Andrew J. Pennington, Millville, N. J.

Application April 5, 1949, Serial No. 1,813

Term of patent 7 years

(Cl. D26—14)

To all whom it may concern:

Be it known that I, Andrew J. Pennington, a citizen of the United States, residing at Millville, in the county of Cumberland and State of New Jersey, have invented a new, original, and ornamental Design for an Antenna Pole Base, of which the following is a specification; reference being had to the accompanying drawings, forming a part thereof.

Figure 1 is a top plan view of an antenna pole base, showing my new design;

Figure 2 is a side elevational view;

Figure 3 is a view similar to Figure 2 but showing the design rotated 90° about a vertical axis.

I claim:

The ornamental design for an antenna pole base, as shown.

ANDREW J. PENNINGTON.
